(57) CLAIM

The ornamental design for a frozen confection, as shown and described.

DESCRIPTION

FIG. 1 is a perspective view of a frozen confection showing our new design;

FIG. 2 is an inverted front elevational view thereof;

FIG. 3 is an inverted rear elevational view thereof;

FIG. 4 is an inverted first side view thereof;

FIG. 5 is an inverted second side elevation view thereof taken on a side opposite the first side;

FIG. 6 is a top plan view thereof; and,

FIG. 7 is a bottom plan view thereof.

The broken lines shown in FIGS. 1, 2, 3, 4, 5 and 7 are for illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.

The broken lines shown in FIGS. 1, 2, 3, 4, 5 and 7 are for

illustrative purposes only and form no part of the claimed

design.
